UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

ENVELOP-BLANK CUTTING AND FORWARDING MECHANISM.

1,310,923.

Specification of Letters Patent. Patented July 22, 1919.

Continuation of application Serial No. 26,675, filed May 8, 1915. This application filed October 17, 1917. Serial No. 197,023.

To all whom it may concern:

Be it known that I, ABRAHAM NOVICK, a citizen of the United States, and a resident of the city of New York, county of Kings, 5 and State of New York, have invented certain new and useful Improvements in Envelop-Blank Cutting and Forwarding Mechanism, of which the following, together with the accompanying drawings, is a specification.

10 The present invention relates to mechanism for cutting envelop blanks and the like from a continuous web or strip of material, and for forwarding said blanks successively, 15 for further operations thereon, such as gumming and folding. The present application constitutes a continuation of my copending application Serial No. 26,675, filed May 8, 1915, and allowed August 22, 1917.

20 The present invention contemplates the formation, with the least possible waste of material, of blanks for making the so-called high-back or high-cut envelopes, from a continuous web of paper. Heretofore, in the 25 formation of blanks from a continuous web, it has been proposed to form all the blanks in the same relative position to the web, which has resulted in excessive waste of stock, or else has confined this method to 30 blanks substantially rhomboidal in form, suitable only for the so-called low-back or low-cut envelopes. It has been discovered that blanks for high-cut or high-back envelopes can be formed from a continuous 35 web, with equal facility and without waste of stock, by disposing successive adjacent blanks in relatively opposite positions with respect to the web. The present invention aims to utilize this advantage in the 40 provision of a mechanism which first cuts oppositely disposed blanks from the continuously moving web, and thereafter causes all of said blanks to assume the same relative position, in readiness for movement in a uniform path for further operations thereon, 45 as by a single set of folding devices.

The above and other objects are attained by the mechanism which is set forth in detail hereinafter, reference being had to the 50 accompanying drawings, in which—

Figure 1 is a plan view of blank cutting and forwarding mechanism embodying my invention.

Fig. 2 is a longitudinal sectional view on the line 2—2 of Fig. 1. 55

Fig. 3 is a transverse sectional view on the line 3—3 of Fig. 1.

Fig. 4 is a detail view, in side elevation, of a part of the mechanism which is shown in Fig. 3. 60

Figs. 5 and 6 are fragmentary plan views illustrating the operation of moving a blank from its cut position into a position for further movement, in a uniform path, through the machine. 65

Figs. 7 and 8 are views similar to Figs. 5 and 6, showing the same mechanism in operation upon a different blank, the blank of Figs. 7 and 8 being formed from the web in an opposite relation to the blank of Figs. 5 and 6. 70

Fig. 9 is a diagrammatic view, illustrating the manner in which the continuous web is cut to form the oppositely disposed blanks, and the manner in which said blanks are 75 turned, after cutting, to occupy the same relative positions for further movement in a uniform path.

Fig. 10 is a plan view of one of the web cutting devices used in the formation of the 80 blanks.

Fig. 11 is an enlarged view illustrating one of the cutters employed on the device of Fig. 10.

Fig. 12 is a perspective view of a web 85 severing device for separating adjacent oppositely disposed blanks.

Like reference characters refer to like parts in the different figures.

Referring first to Figs. 1 and 2, the mechanism is herein shown as carried between longitudinal side frames 1, 1, which support at one end a shaft or reel 2 for a roll of material 3, from which the web A is continuously drawn. The side frames 1, 1 provide journals for a main driving shaft 4 which carries a belt pulley 5 for actuation from any suitable source of power, not shown. The shaft 4 carries a pinion 6 which is in mesh with a gear 7 on a counter-shaft 8, the latter driving, through an idler 9, the intermeshing gears of a pair of feed rolls 10, 10 for advancing the web A through the machine. 90 95 100

In front of the feed rolls 10, 10 are disposed a pair of co-operating cutting rolls 11, 105

12, having intermeshing gears which are also actuated by the idler 9, as shown in Fig. 2. One of said rolls, here shown as the roll 12, carries cutting devices 13, 14, Fig. 10, for operation on the continuously traveling web A to blank out the gore shaped pieces 13', 14', Fig. 9, in the formation of the blanks from said web. Said roll 12 also carries cutting devices 15 and 16, to blank out the re-entrant angles 15' and 16', Fig. 9, in the opposite edges of adjacent blanks. Said roll 12 also carries a cutting device 17, Figs. 2 and 11, and in alinement therewith a pair of devices 18 and 19, Fig. 2, similar to the devices 15 and 16, for blanking out the aperture 17' and the re-entrant angles 18' and 19' in the web A, as shown clearly in Fig. 9. The above described cutting devices on the roll 12 preferably operate in opposition to a hardened surface 20 on roll 11, and each cycle of operations thereof serves to form the cuts 13', 14', 15', 16', 17', 18' and 19' in the web A.

The above described cutting operations are ordinarily not sufficient to remove the waste material or chips from the web, since all the fibers of the material are not completely severed. For the removal of said chips, any suitable chip removing mechanism may be employed, such as that shown and described in my copending application Serial No. 182,025, filed July 21, 1917. As herein shown, a pair of chip removing rolls 21, 21 have intermeshing gears driven from an idler 22, which in turn is driven from the roll 12 of the blank cutting mechanism; said rolls 21, 21 are shown as equipped with mechanism for withdrawing the waste material or chips previously formed in the web at 13', 14', 15', 16', 17', 18' and 19', but since said chip removing mechanism forms no part of the present invention, a detailed description thereof is unnecessary. As the web emerges from said chip removing rolls, it presents the appearance indicated near the center of Fig. 9, and in this condition it is carried forward between the bight of forwarding rolls 23, 23, which have intermeshing gears driven from an idler 24, that is driven in turn from the lower chip removing roll 21.

In advance of the forwarding rolls 23, 23 are provided web severing rolls 25 and 26, one of which, in the present instance the roll 26, carries cutting devices 27 and 28, as shown in Fig. 12, for severing the web on the transverse lines 27' and the oblique lines 28' respectively, as shown in Fig. 9. To this end the other cutting roll 25 may be formed, if desired, with a hardened outer surface for co-operation with said cutting devices 27 and 28, and preferably also said roll 25 is disposed with its axis slightly oblique to the axis of roll 26, as shown in Fig. 1, so that

the cutting device 27 will gradually cut across the web and thereby produce a shearing action which insures complete severance of the fibers. The cutting rolls 25 and 26 carry intermeshing gears, and are driven by an idler 29 which in turn derives its rotation from the lower web forwarding roll 23, as shown in Fig. 2. The action of these cutting rolls 25 and 26 is such that the blanking out of the web into a succession of oppositely disposed blanks is completed, as shown in Fig. 9, and as also shown in said figure, the blanks emerge from said rolls in alternating relation, viz., first a right hand blank, so-called, as indicated at 30, presenting an advancing edge which is oblique, and then a left hand blank, so-called, as indicated at 31, presenting a transverse edge, with its oblique edge rearmost.

Each blank thus severed from the web by the cutting rolls 25 and 26 is immediately seized by forwarding rolls 32, 33, which operate at a higher speed than the web forwarding rolls 23, 23 so as to space each severed blank from the advancing edge of the web, as shown at 34, 34, Fig. 9. With the blanks thus severed and separated, it becomes necessary, if they are to be further acted upon by the same mechanism, to dispose them all in a uniform position for further advancement, and to this end the invention contemplates the provision of a suitable blank turning mechanism for action upon the oppositely disposed adjacent blanks 30 and 31 to bring them into a uniform position. To prevent interference with the operation of this blank turning mechanism, which will be described hereinafter, one of the forwarding and accelerating rolls, in the present instance the roll 32, is preferably made with a segmental cutaway portion 35, in order to insure the release of the rear edge of a blank as soon as its forward edge comes under the influence of the turning mechanism. The rolls 32 and 33 have suitable intermeshing gears which are driven from an idler 36, the latter in turn deriving its rotation from the forwarding roll 26, as shown in Fig. 2.

From the forwarding rolls 32 and 33, each severed blank 30 or 31 passes between pairs of fingers 37 and 38. The lower fingers 38 are stationary, while the upper fingers are carried on a rock shaft 39 which is actuated by an arm 40, having a cam roll bearing against a cam 41 on the shaft of segmental roll 32. The action of this cam is such that the fingers 37 and 38 remain separated while the blank is under the influence of rolls 32 and 33; thereafter, as the blank passes into the blank turning mechanism, as hereinafter described, the cam 41 allows the fingers 37 to descend and rest by gravity on the blank, to retard the same and reduce its

momentum, preliminary to the turning operation. The disks 42 and 43, in advance of said fingers, have suitable intermeshing gears which are driven from an idler 44, the latter in turn being driven from the gear of roll 33, as shown in Fig. 2.

The blank turning mechanism which receives the blanks from the forwarding disks 42 and 43 is carried by a transverse supplemental framework 45 which extends inwardly from the front side frame 1. The framework 45 supports a pair of oppositely facing turning members 46 and 47 which are normally spaced apart to receive the blank in the plane of its forward movement by the disks 42 and 43, the lower member 46 being vertically fixed and the upper member 47 being capable of movement toward and away from the member 46, as hereinabove described. The vertical movable member 47 has a spindle 48, which is journaled in the upper part of framework 45 and is capable of axial movement therein. A spring 49, acting between the member 47 and the stationary bearing of spindle 48, tends to yieldingly press the member 47 toward the member 46, and this action is opposed by a lever 50 pivoted at 51 on framework 45, and bearing upwardly against a nut 52 on the upper end of spindle 48. The opposite end of lever 50 is pivotally connected by a link 53 with a swinging arm 54, which is pivoted at 55 and carries a cam roll 56 for co-operation with a cam 57 on the shaft of disk 42. The high part of cam 57 maintains the member 47 in elevated position until a blank is disposed between the members 46 and 47; thereafter the cam allows the spring 49 to depress the member 47 and thus to grip the blank against the member 46, preliminary to the turning operation.

For the accomplishment of this turning operation, the members 46 and 47, when in position to clamp the blanks as above described, are given predetermined joint movements of oscillation, in one direction to rotate a right hand blank 30 into the desired position, and in the other direction to rotate a left hand blank 31 into the same position. To this end the spindle 48 of member 47 is adapted to be oscillated in unison with a vertical fixed spindle 58 attached to member 46 and having a journal bearing in the lower part of framework 45. The two spindles 48 and 58 have similarly disposed rock arms 59, 59 extending radially therefrom, the rock arm for the vertical movable spindle 48 having a spline connection which permits axial movement of said spindle for the purpose above described. The ends of arms 59, 59 are connected by links 60, 60 to arms 61, 61 extending from an actuating rock shaft 62 which is journaled in the framework 45. Said actuating rock shaft 62

is oscillated by means of a rock arm 63, 65 whose free end carries a cam roll 64 in the cam groove 65 of a rotating horizontal disk 66.

The disk 66 is suitably supported by a yoke or bearing 67 carried inwardly from the front side frame 1, and is operated by bevel gearing 68 from a transverse shaft 69 which derives its rotation, through gear 70, from the idler 44, as shown in Figs. 2 and 3. The contour of cam groove 65 is such that upon the disposal of a right hand blank 30 between the members 46 and 47, as shown in Fig. 5, and the clamping of said blank between said members, the actuating shaft 62 will be rocked to move the spindles 48 and 58 in a clockwise direction, and thus to carry said blank into the position shown in Fig. 6. Thereafter, the contour or groove 65 maintains the members 46 and 47 against rotation while the member 47 is being raised by spring 49 to release said blank 30, and to permit the removal of said blank by rolls 71 and 72, as hereinabove described. With the turning mechanism in this condition, a left hand blank 31 is then projected between the members 46 and 47, as shown in Fig. 7, and thereafter, upon the clamping of said blank by the descent of member 47, the cam groove 65 causes the actuating rock shaft 62 to move counter-clockwise, thus carrying the left hand blank 31 into the position illustrated in Fig. 8, which is the same relative position as that shown in Fig. 6 for the right hand blank 30. The blank turning mechanism thus operates in opposite directions upon successive adjacent oppositely disposed blanks to move them into the same relative positions with respect to the rolls 71 and 72. The arrival of a blank between the members 46 and 47, in position for the inauguration of the above described turning movement, is substantially coincident with the release of said blank by the disks 42 and 43, owing to the provision of a segmental cutaway portions 73 in the disks 42. That is to say, the disks 42 are so timed and proportioned that their edges 74 release the blanks 30 and 31 when they arrive in the proper position to be turned, as illustrated in Figs. 5 and 7 respectively, and at this instant, in each case, the finger 37 descends upon the rear edge of the blank to arrest its further movement. The turning of a blank as above described draws its rear edge from beneath the gravity resting fingers 37, and this turning takes place while the segmental cutaway portions 73 of disks 42 are moving over said blank.

The rolls 71 and 72 which receive the blank from the turning mechanism are disposed parallel with the longer axis of the blank in the position occupied by said axis after the turning movement is completed. These rolls have intermeshing gears to in-

sure their rotation in unison, and are journaled in oblique side frames 75, 75 extending in the new direction of movement of the blanks. To permit the projection of the 5 blanks between said rolls 71 and 72, the roll 71 has a segmental cutaway portion 76 and is so timed that this portion will pass above the blank during the latter's turning movement. After the blank has been completely 10 turned, the roll 71 becomes operative with the roll 72 to remove the blank from the turning mechanism and to advance the same into the bight of cylindrical rolls 77, 77 from which it may pass onto belts 78, 78, or 15 other suitable mechanism for conveying it forward for further operations. Thus all of the blanks are turned into the same relative position with respect to the machine, and are capable of being moved forward in 20 the same path for further operation thereon, for instance, by a single set of gumming and folding devices, notwithstanding the initial disposition of said blanks in opposing relation, as originally cut from the web A. 25 In other words, as shown in Fig. 9, all the blanks are finally caused to move in the direction indicated by the arrow B, in the same path, and with their extended flaps disposed symmetrically with respect to the 30 line of travel, whereby the several reentrant angles defining the lines of fold of the completed envelop, become available for centering and squaring the blanks preliminary to the operation of the single set of gumming, creasing and folding devices, just as 35 though the blanks had been fed uniformly from a stack or pile.

For driving the rolls 77 and belts 78, a counter-shaft 79 is suitably journaled on the 40 front oblique frame member 75, said counter-shaft having a bevel gear connection 80 with a shaft 81 that is driven in turn by bevel gearing 82 from the main driving shaft 4. The shaft 79 drives the rolls of 45 belts 78 through bevel gearing 83, and the intermeshing gears of rolls 72 and 77 may be driven therefrom through idlers 84 and 85, as shown in Fig. 2.

I claim,

50 1. In mechanism of the class described, the combination with means for cutting a series of oppositely disposed envelop blanks from a web, of a blank turning mechanism operable in opposite directions upon successive adjacent blanks, and means for advancing the 55 blanks in single file, uniformly disposed, for further operation.

2. In mechanism of the class described, the combination with means for forming a 60 series of oppositely disposed envelop blanks from a web, of means for advancing said blanks, a blank turning mechanism operable in opposite directions upon successive adjacent blanks, and means for advancing the

blanks in single file, uniformly disposed, 65 for further operation.

3. In mechanism of the class described, the combination with means for cutting a series of oppositely disposed envelop blank from a continuous running web, a blank 70 turning mechanism operable in opposite directions upon successive adjacent blanks, and means for advancing the blanks in single file, uniformly disposed, for further operation. 75

4. In mechanism of the class described, the combination with means for forming a series of oppositely disposed envelop blanks from a continuous running web, of means for accelerating successively formed blanks, 80 a blank turning mechanism operable in opposite directions upon successive adjacent blanks, and means for advancing the blanks in single file, uniformly disposed, for further operation. 85

5. In mechanism of the class described, the combination with means for successively cutting oppositely disposed envelop blanks from a continuously running web, of mechanism for turning the blanks from the oppositely disposed positions into a single predetermined position, and means for advancing the turned blanks in a uniform path. 90

6. In mechanism of the class described, the combination with means for successively cutting oppositely disposed envelop blanks from a continuously running web, of mechanism for turning the blanks from the oppositely disposed positions into a single predetermined position, and means for advancing 100 the blank from the last named position in single file for further operation thereon. 95

7. In mechanism of the class described, the combination with means for successively cutting oppositely disposed envelop blanks from a continuously running web, of means for accelerating the blanks, mechanism for turning the blanks from the oppositely disposed positions into a single predetermined position, and means for advancing the 110 turned blanks in a single path for further operation. 105

8. In mechanism of the class described, the combination with means for forwarding a continuous web, means for forming oppositely disposed envelop blanks from said web, mechanism for severing the blanks from the web, a forwarding means for the severed blanks, and means for uniformly disposing the severed blanks between the severing mechanism and the blank forwarding means. 115

9. In mechanism of the class described, a cutting mechanism for forming a succession of envelop blanks, oppositely disposed, from 125 a web, and an oscillating gripper, operable at each end of its oscillatory movement, for alternately gripping and releasing said

- blanks, the blanks when gripped being disposed opposite to one another and the blanks after release being uniformly disposed to one another.
- 5 10. In mechanism of the class described, a cutting mechanism for forming a succession of envelop blanks, oppositely disposed, from a web, an oscillating gripper, operable at each end of its oscillatory movement, for alternately gripping and releasing said blanks, the blanks when gripped being disposed opposite to one another and the blanks after release being uniformly disposed to one another, and means for advancing the released blanks in single file for further operation.
11. In mechanism of the class described, a cutting mechanism for forming a succession of envelop blanks, oppositely disposed, from a web, an oscillating gripper for gripping a blank at each end of its oscillatory movement, and releasing said blank at the opposite end of its oscillatory movement, each blank when gripped being disposed opposite to the blanks adjacent thereto, and all the blanks after release being uniformly disposed to one another, and means for advancing the blanks from the gripper in single file for further operation thereon.
- 20 12. In mechanism of the class described, a cutting mechanism for forming a succession of envelop blanks, oppositely disposed, from a web, an oscillating gripper, with its axis of oscillation normal to the plane of the blanks, for gripping a blank at each end of its oscillatory movement, and for releasing said blank at the opposite end of its oscillatory movement, the blanks before gripping being disposed opposite to one another and the blanks after release being uniformly disposed to one another, and means for advancing the blanks from the gripper in single file widthwise of the web for further operation thereon.
- 25 13. The combination with means for forwarding a continuous web, means for forming a series of oppositely disposed envelop blanks from said web, means for severing the blanks from the web, rolls for forwarding each severed blank at an advanced speed, means for releasing the severed blank from said rolls, and means for intermittently holding the blank between said rolls.
- 30 14. The combination with means for forwarding a continuous web, means for forming oppositely disposed envelop blanks from said web, means for severing the blanks, means for forwarding the severed blanks at an advanced speed, comprising two pairs of rolls capable of alternately engaging and releasing a severed blank, and means for holding the blank as it is released by said second pair of rolls.
- 35 15. The combination with means for forwarding a continuous web, of means for forming a series of envelop blanks therefrom, means for severing the blanks from the web, means for forwarding the severed blank at an advanced rate of speed, comprising rolls arranged to alternately engage and release the severed blank, means for holding the blank, and means for bringing said blank holding means into action as the blank is released from said forwarding rolls.
- 40 16. In mechanism of the class described, the combination with means for forwarding successive blanks in a row, each alternate blank being oppositely disposed to the other blanks in the row, of a blank turning means operable to dispose all of the blanks, successively, in the same position.
- 45 17. In mechanism of the class described, the combination with means for forwarding successive blanks in a row, each alternate blank being oppositely disposed to the other blanks in the row, of a blank turning means operable to dispose all of the blanks, successively, in the same position for further advancement in a uniform path.
- 50 18. In mechanism of the class described, the combination with cutting mechanism, operable on an advancing web of material to form a succession of blanks, each alternate blank being oppositely disposed to the other blanks thus cut, of a blank turning means operable to dispose all of the blanks, successively, in the same position, and means for forwarding said blanks successively from said position in a uniform path.
- 55 19. In mechanism of the class described, the combination with means for forwarding successive blanks in a row, each alternate blank being oppositely disposed to the other blanks in the row, of a blank turning means operable to dispose all of the blanks, successively, in the same position for further advancement in a uniform path at an angle to the original direction of advancement of said blanks.
- 60 20. In mechanism of the class described, the combination with cutting mechanism, operable on an advancing web of material to form a succession of blanks, each alternate blank being oppositely disposed to the other blanks thus cut, of a blank turning means operable to dispose all of the blanks, successively, in the same position, and means for forwarding said blanks successively from said position in a uniform path at an angle to the original direction of advancement of said web.

Dated this 13th day of Sept., 1917.
